US00D925612S

(12) **United States Design Patent** (10) **Patent No.:** **US D925,612 S**
(45) **Date of Patent:** **** Jul. 20, 2021**

(54) **PIPE LIFTING ELEVATOR BODY**

(71) Applicant: **FORUM US, INC.**, Houston, TX (US)

(72) Inventor: **Frederik Stoldt**, Hamburg (DE)

(73) Assignee: **FORUM US, INC.**, Houston, TX (US)

(**) Term: **15 Years**

(21) Appl. No.: **29/683,583**

(22) Filed: **Mar. 14, 2019**

(51) LOC (13) Cl. **15-04**

(52) U.S. Cl.

USPC **D15/21**

(58) **Field of Classification Search**

(57) **CLAIM**

The ornamental design for a pipe lifting elevator body, as shown and described.

DESCRIPTION

FIG. 1 is a top front perspective view of a pipe lifting elevator body showing my new design;

FIG. 2 is a top rear perspective view thereof;

FIG. 3 is a bottom front perspective view thereof;

FIG. 4 is a bottom rear perspective view thereof;

FIG. 5 is a front elevational view thereof;

FIG. 6 is a right side elevational view thereof;

FIG. 7 is a rear elevational view thereof;

FIG. 8 is a left side elevational view thereof;

FIG. 9 is a top plan view thereof;

FIG. 10 is a bottom plan view thereof;

FIG. 11 is a sectional view thereof taken along line 11-11 of FIG. 8;

FIG. 12 is a sectional view thereof taken along line 12-12 of FIG. 8;

FIG. 13 is a sectional view thereof taken along line 13-13 of FIG. 8;

FIG. 14 is a sectional view thereof taken along line 14-14 of FIG. 8;

FIG. 15 is a sectional view thereof taken along line 15-15 of FIG. 8; and,

FIG. 16 is a sectional view thereof taken along line 16-16 of FIG. 8.
